UNITED STATES PATENT OFFICE

BERNARD JOHN GARRIS, OF WILMINGTON, DELAWARE

SPRING OR RESILIENT WHEEL

Application filed May 13, 1931. Serial No. 537,143.

This invention relates to a spring or resilient wheel designed primarily for use in connection with the landing gear of airplanes, but it is to be understood that a wheel, in accordance with this invention may be employed in any connection for which it is found applicable, and the invention has for its object to provide, in a manner as hereinafter set forth, a spring or resilient wheel so constructed and arranged to give the necessary resiliency, yielding or cushioning capacity during the take off and landing of an airplane when the latter is travelling over an uneven road surface and whereby such capacity or characteristic is acquired without the necessity of employing pneumatic tires.

Further objects of the invention are to provide, in a manner as hereinafter set forth, a spring or resilient wheel which is comparatively simple in its construction, strong, durable, compact, thoroughly efficient in its use for the purpose intended, readily assembled, capable of being quickly repaired when occasion requires, and comparatively inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to, which fall within the scope of the claims hereunto appended.

In the drawings wherein like reference characters denote corresponding parts throughout the several views:

Figure 1 is a vertical sectional view of a spring or resilient wheel in accordance with this invention.

Figure 2 is a section on line 2-2 Figure 1.

Figure 3 is a disassembled view in perspective of the pivotally mounted form of spoke guide.

Figure 4 is a perspective view of the form of spring compressing lever employed.

Referring to the drawings the wheel includes a felly 1 constructed from any suitable material and formed with a series of V-

shaped openings 2 spaced an equal distance from each other. The openings 2 extend from the inner to the outer edge of the body of the felly 1.

The inner edge of the felly 1 between each pair of V-shaped openings 2 is formed with a pocket 3 having its ends positioned in proximity to the openings of the pair. The length of the pocket 3 is materially greater than the width thereof. Each end wall of the pocket 3 and which is indicated at 4 is upon a compound curve. The end walls 4 are oppositely disposed with respect to each other.

Projecting into each pocket 3 is a pair of oppositely extending and oppositely disposed spring compressing levers 5 and with each lever of a length to have one end thereof project beyond an end wall of the pocket to a point inward of the inner end of an opening 2.

Each lever 5 includes a substantially triangular shaped body part 6 having one side thereof of compound curvature to seat against an end wall of a pocket 3. In proximity to the apex of body part 6, the latter is mounted on a pivot 7 which is secured to the felly 1 and extends transversely of a pocket 3 in proximity to an end wall 4 thereof. Projecting from one corner of the base of body part 6 is a laterally extending bifurcated arm 8 which tapers towards its free end. Projecting from the other corner of the base of body part 6 is a laterally disposed apertured arm 9 arranged inwardly with respect to the arm 8. The body part 6 is formed with an opening 10 for the passage of the pivot 7. The aperture in arm 9 is indicated at 11 and the furcation in arm 8 at 12. The arms 8 and 9 are angularly disposed with respect to each other. The opening 10 is eccentrically disposed with respect to body part 6.

The number of spokes of the wheel can be as desired, but preferably six in number and is so illustrated. The spokes are indicated generally at 13, 14, 15, 16, 17 and 18. The spokes are of a length to extend into the openings 2. Associated with the outer end of each spoke is a combined pivoted guide and bearing therefor and which consists of a tubular member 19 provided at its inner end with

a pair of oppositely extending pins 20 constituting pivots therefor. The pins 20 are mounted in bearings 21 secured by holdfast devices 22 to the inner edge of the felly 1. 5 The bearings 21 are arranged at each side of the inner end of an opening 2 and extends lengthwise of the latter. The pins 20 are disposed at right angles to the direction of the length of the openings 2, and the latter permits the member 19 shifting in opposite directions therein.

Each spoke includes an intermediate part 23, an outer part 24 and an inner part 25. Preferably the part 24 is of circular cross 15 section, uninterrupted from end to end and of uniform diameter throughout and slides within the tubular member 19. The intermediate part 23 consists of a straight portion 26 of uniform diameter throughout which merges into a flaring portion 27 formed with an outwardly directed annular flange 28. The part 24 is formed integral centrally of the outer face of the flaring portion 27, and spaced from the flange 28. The inner part 25 consists of a rear portion 29 in the 20 form of an annulus and a curved portion 30 offset with respect to the portion 29 and merging into the inner end of the intermediate part 23. The parts 23, 24 of one spoke are 25 arranged in alignment with the parts 23, 24 of adjacent spokes. The spokes 13, 16 are oppositely disposed with respect to each other. The spokes 14, 17 are oppositely disposed with respect to each other and the 30 spokes 15, 18 are oppositely disposed with respect to each other. The inner portions 29 of the spokes 13, 16 abut each other. The inner portion 29 of the spoke 14 abuts the inner portion 29 of the spoke 13. The inner portion 29 of the spoke 15 abuts the inner portion 29 of the spoke 14. The inner portion 29 of the spoke 18 abuts the inner portion 29 of the spoke 16. The inner portion 29 of the spoke 17 abuts the inner portion of the spoke 45 18. The curved portions 30 of the spokes are so set up as to position parts 23 of the spokes in opposed spaced alignment and the parts 24 of the spokes in opposed spaced alignment. The portion 26 of the intermediate part 23 of each spoke is formed with a diametrically disposed opening 31 in proximity to the curved portion 30 of the inner part 25 of the spoke.

Slidably mounted on the part 24 of each spoke is an apertured abutment disc 32 having its inner face formed with an annular groove 33. Interposed between the disc 32 and the portion 27 of the spoke is a coiled cushioning spring 34 which surrounds the outer part 24 of the spoke. 55 60 Each spoke extends between a pair of equalizing elements. The elements of each pair are indicated at 35 and are of like construction and bodily shift together. The elements of each pair, centrally thereof are mounted on a pivot pin 36 which extends

through the opening 31 formed in the spoke.

Pivots connected, as at 37, 38 to the ends of each pair of equalizing elements are oppositely extending tensioning rods 39, 40 respectively and each of which has a threaded portion 41, carrying an adjusting nut 42. The rods extend through the openings 11 formed in the levers 5 and the nuts 42 abut against the inner faces of the arms 9 of the levers 5. The rod 39 associates with one 75 lever 5 of the pair of levers 5 and the bar 40 associates with one lever 5 of an adjacent pair of levers.

The portions 29 of the spokes are arranged in abutting relation and extending therethrough is a bushing 43 which is positioned on an axle 44 having reduced peripheral threaded ends 45. Positioned on the reduced ends 45 and abutting the ends of the bushing 43 as well as the outer portions 29 of the series of outer portions 29 of the spokes are abutment discs 46.

Mounted on the reduced portions 45 are cover members 47 in the form of apertured discs of concavo-convex cross sections. The members 47 are positioned against the inner faces of the abutment discs 46. Threadedly engaging with the reduced portions 45 and clamping against the members 47 are securing nuts 48. The reduced portions 45 project outwardly from the nuts 48.

Positioned against opposite sides of the felly 1 as well as being fixedly secured therewith is a pair of cover members 49, each in the form of an annulus and having the inner portion thereof out curved and opposing the inner face of the member 47. The members 49 bodily shift with the felly 1 inwardly and outwardly with respect to the opposed faces of the members 47. The members 47 and 49 100 105 coact to conceal the spokes, felly, cushioning springs, axle 44 and abutment discs 46.

Secured upon the reduced portions 45 of the axle 44 and enclosing the nuts 48 are cap members 50 provided with bearing cones 51 110 which are adapted to be connected in any suitable manner with the frame of the landing gear to revolvably support the wheel.

Mounted against the felly 1 is a solid tire 52 of cushioning material. The members 49 115 have their outer edges flanged in a manner, as at 53 for clinching the sides of the tire 52.

The outer ends of the bars 39, 40 extend into the pockets 3 and the latter provide clearances for such outer ends. The nuts 42 support the arms 9 of the levers 5 and the openings 11 in said arms 6 are of a size and contour to permit of the nuts 42 when shifted to adjust the levers 5 on the rods 39, 40. The abutment discs 42 are positioned against the inner arm 8 of each pair of opposed inner arms 8 when the levers 5 are set up in active position. The arms 8 of each pair of opposed arms 8 slide relatively to each other when the levers from which said arms extend 120 125 130

are shifted on their pivots. The springs 34 resiliently support the felly to set up a yielding or cushioning characteristic when the wheel is travelling over an uneven road surface. The shifting bodily of the felly relative to the axis of the wheel is had against the action of the springs 34.

The members 19 also provide means for coupling the felly with the spokes whereby the former will be carried with the latter, but is capable of bodily shifting relative to the axis of the wheel.

What I claim is:—

1. In a resilient wheel, a felly bodily shiftable relative to the axis of the wheel, cushioning springs, a set of independent spokes, each spoke having its inner part in the form of an annulus, means for clamping said inner parts to an axle to provide for said set to bodily move with the axle, said spokes having means for receiving the inner ends of said springs, abutment discs positioned against the outer ends of said springs, pivoted means for slidably connecting the spokes with said felly, spring compressing levers interposed between said abutments and the felly, and equalizing elements pivotally connected with the spokes and adjustably connected to said levers.

2. In a resilient wheel, a felly bodily shiftable relative to the axis of the wheel, cushioning springs, a set of independent spokes, each spoke having its inner part in the form of an annulus, means for clamping said inner parts to an axle to provide for said set to bodily move with the axle, said spokes having means for receiving the inner ends of said springs, abutment discs positioned against the outer ends of said springs, pivoted means for slidably connecting the spokes with said felly, spring compressing levers interposed between said abutments and the felly, equalizing elements pivotally connected with the spokes and adjustably connected to said levers, said felly provided with openings to form clearances for the pivoting movement of said spoke connecting means, and a tire mounted on and connected with the felly.

3. In a resilient wheel, a felly bodily shiftable relative to the axis of the wheel, cushioning springs, a set of independent spokes, each spoke having its inner part in the form of an annulus, means for clamping said parts to an axle to provide for said set to bodily move with the axle, said spokes provided with means for receiving the inner ends of said springs, pivoted means for slidably connecting the outer ends of the spokes to said felly whereby the latter will be carried with the spokes, abutments slidably mounted on the spokes and positioned against the outer ends of the springs, overlapping spring compressing levers pivotally connected with the felly and interposed between the latter and

said abutments, and an equalizing means carried by the spokes and adjustably connected to said levers.

4. In a resilient wheel, a felly bodily shiftable relative to the axis of the wheel, cushioning springs, a set of independent spokes, each spoke having its inner part in the form of an annulus, means for clamping said parts to an axle to provide for said set to bodily move with the axle, said spokes provided with means for receiving the inner ends of said springs, pivoted means for slidably connecting the outer ends of the spokes to said felly whereby the latter will be carried with the spokes, abutments slidably mounted on the spokes and positioned against the outer ends of the springs, overlapping spring compressing levers pivotally connected with the felly and interposed between the latter and said abutments, an equalizing means carried by the spokes and adjustably connected to said levers, said felly provided with V-shaped openings to form a clearance for the pivoting movement of the means for slidably connecting the spokes to the felly and telescopic covering means having outer and inner sections, the inner sections being clamped to the spokes and the other sections secured to the felly.

5. In a resilient wheel, independent spokes, means for clamping the inner ends of the spokes with an axle, a felly, means carried by the spokes and pivoted to the felly for resiliently supporting the latter, pivoting devices for slidably connecting the spokes to the felly, and equalizing devices pivotally connected to the spokes and adjustably connected to said means.

6. In a resilient wheel, independent spokes, the inner parts of said spokes being in the form of an annulus, means for clamping the inner parts of the spokes with an axle, a felly, means carried by the spokes and eccentrically pivoted to the felly for cushioning the latter, pivoted devices for slidably connecting the spokes to the felly, and equalizing devices pivotally carried by the spokes and adjustably connected to said means.

7. In a resilient wheel, independent spokes, the inner parts of said spokes being in the form of an annulus, means for clamping the inner parts of the spokes with an axle, a felly, means carried by the spokes and eccentrically pivoted to the felly for cushioning the latter, pivoted devices for slidably connecting the spokes to the felly, and equalizing devices pivotally carried by the spokes and adjustably connected to said means, and said felly provided with clearances for said pivoted and equalizing devices.

In testimony whereof, I affix my signature hereto.

BERNARD JOHN GARRIS.
